UNITED STATES PATENT OFFICE.

ARMOND D. MATHYS, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

DESIGN FOR A TIRE.

Application filed December 31, 1923. Serial No. 8,205. Term of patent 14 years.

To all whom it may concern:

Be it known that I, ARMOND D. MATHYS, am my new design, while Figure 2 is a citizen of the United States, residing at Milwaukee, in the county of Milwaukee and 1, taken on the line 2—2 of Figure 1. I, ARMOND D. MATHYS, have invented a new, original, and ornamental Design for a Tire, of which the following is a specification, reference being had to the accompanying drawing, which forms a part thereof, and in which—

Figure 1 is a plan view of a tire showing my new design, while Figure 2 is a sectional view of the tire shown in Figure

I claim:

The ornamental design for a tire substantially as shown.

ARMOND D. MATHYS.
